UNITED STATES PATENT OFFICE.

LUTHER STIERINGER, OF NEW YORK, N. Y., ASSIGNOR TO THE EDISON ELECTRIC LIGHT COMPANY, OF SAME PLACE.

SAFETY-CATCH FOR ELECTRIC-LIGHT CIRCUITS.

SPECIFICATION forming part of Letters Patent No. 281,576, dated July 17, 1883.

Application filed March 16, 1883. (No model.)

To all whom it may concern:

Be it known that I, LUTHER STIERINGER, of New York city, in the county and State of New York, have invented a certain new and useful Improvement in Safety-Catches for Electric-Light Circuits, of which the following is a specification.

Heretofore in the use of lead or other wire fusible at a low heat, for the safety-catches of electric-light circuits, it has been usual to secure the wire in circuit by clamping it directly beneath the heads of binding-screws. I have found that a good and lasting contact cannot be made in this way between the lead wire and binding-screws, and that many safety-catches are destroyed by the heating of the contacts without an abnormal flow of current, against which they are designed to guard. This poor contact is due to the small binding-surface of the screws on the wire, to the ready oxidation of the lead, and to the fact that the screws cannot be forced down hard upon the lead by reason of its lack of elasticity, its softness, and the danger of cutting off the wire by the heads of the screws; hence the screws soon work loose, and the oxidation and heating of the contacts and the destruction of the safety-catches are the inevitable results.

The object, therefore, of my invention is to overcome this difficulty, which I do by soldering or fusing the lead or other safety-catch wire to terminals of other and harder and elastic metal, upon which the binding-screws bear. Copper plates are preferred, having holes or notches through which the screws pass.

The invention further relates to the construction of a fusible safety-catch, designed more especially to carry heavy or main-line currents, which will not be subject to the disadvantages of safety-catches breaking the circuit at one point only, resulting from the intense heat centered at that point, and will also permit of a ready change in the carrying capacity of the safety-catch; and the invention also includes means for preventing the cutting or breaking of the safety-catches when the binding-screws are forced down upon the end plates, for permitting the replacement of the safety-catches without removing the binding-screws, and for preventing the danger from

firing or carbonizing the parts supporting and surrounding the safety-catches, all as more fully hereinafter explained.

In the accompanying drawings, forming a part hereof, Figure 1 is a top view of the safety-catch for heavy or main-line currents; Fig. 2, a vertical section of the same; Fig. 3, a separate perspective view of one end of a safety-catch placed on its support, but not secured; Fig. 4, a top view of one end of a safety-catch; Fig. 5, a perspective view of a form of safety-catch having one fusible link, and Fig. 6 a perspective view of the protecting-cover for the same.

Like letters denote corresponding parts in all the figures.

A is the fusible safety-catch link, composed of lead or other suitable metal or alloy fusible at a low heat. It is soldered or fused at its ends to plates B of some hard and elastic metal, for which purpose copper is preferred. The plates B are provided with slots b, extending inwardly from their ends, and are held by binding-screws a. The binding-screws enter supporting metallic plates or blocks C C', which are mounted upon a non-combustible and non-carbonizable insulating-base, D, capable of withstanding high heat, such as earthenware or glass, or any suitable composition. The binding-screws may have slotted heads; or they may be thumb-screws. The slots in the end plates, B, permit the replacement of the safety-catch by simply loosening the screws a, and without removing them from the plates or blocks C C'. The screws can be set down hard upon the copper end plates, making a good and lasting contact therewith, having a large surface and such low resistance that there will be no danger of heating or oxidizing.

The metallic plates or blocks C C' are provided with angular depressions c, and the plates B are made of the same shape, so that such plates cannot turn and cut the safety-catch link when the binding-screws are forced down upon them. It is evident that the locking of the supporting-blocks and end plates, to prevent the turning of such end plates, could be accomplished in a number of ways differing in specific construction from that shown.

For a main-line safety-catch, or one for heavy

currents, the metallic supporting blocks or plates C C' are made of sufficient length to carry several fusible safety-catch links, which extend from one to the other of the blocks, as shown in Fig. 1, and these blocks have central extensions, E, upon which clamp-plates E' are secured for clamping the circuit-wires F. In this construction the fusible safety-catch links have a multiple-arc relation to each other, and more or less of such links can be used, as required, for the number of lamps to be carried, the number of lamps which each link is capable of carrying being ascertained and preferably stamped on one of the end plates. When this multiple safety-catch is destroyed, it does not go all at once, but the weakest link is first fused and the others in succession.

For a single-link safety-catch the form shown in Fig. 5 may be used, the circuit-wires being secured to extensions of C C'. A cover, G, of the same material as the base D, may be used, and such a cover may also be employed with the multiple safety-catch.

What I claim is—

- 25 1. A fusible safety-catch link having end plates of harder metal, to which the fusible metal is fused or soldered, substantially as set forth.
- 30 2. A fusible safety-catch link having end plates of harder metal fused or soldered thereto, in combination with metallic supports and binding-screws clamping the end plates, substantially as set forth.
- 35 3. A fusible safety-catch link having end plates of harder metal fused or soldered thereto and secured by binding-screws, in combination with means for locking the end plates against turning when the binding-screws are turned, substantially as set forth.

4. A fusible safety-catch link having end 40 plates of harder metal fused or soldered thereto, such end plates being provided with slots for receiving binding-screws, substantially as set forth.

5. A fusible safety-catch secured to metallic 45 supports mounted upon a base of non-combustible and non-carbonizable insulating material, substantially as set forth.

6. The combination of a fusible safety-catch, end plates of harder metal, metallic supports 50 for the end plates, binding-screws, and a base of non-combustible and non-carbonizable insulating material, substantially as set forth.

7. The combination, with a conductor forming one side of an electric circuit, of two or 55 more separate and independently-removable safety-catch links interpolated in such conductor in multiple-arc relation to each other, substantially as set forth.

8. The combination, with metallic plates or 60 blocks and circuit-wires connected therewith, of two or more separate fusible safety-catch links connecting such metallic plates or blocks, substantially as set forth.

9. The combination, with metallic plates or 65 blocks and the circuit-wires connected therewith, of two or more fusible safety-catch links connecting such metallic plates or blocks, such fusible links having end plates of harder metal, and being secured by binding-screws, substantially as set forth.

This specification signed and witnessed this 19th day of February, 1883.

LUTHER STIERINGER.
